TEMPORARY CLOSURE FOR FREIGHT VEHICLE DOORWAY

Barton H. Ford, Omaha, Nebr., assignor of one-half to International Paper Company, New York, N.Y., a corporation of New York, and one-half to The Stanley Works, New Britain, Conn., a corporation of Connecticut

Filed July 25, 1960, Ser. No. 45,035

10 Claims. (Cl. 160—368)

This invention relates to a temporary closure for a freight vehicle doorway. The invention is particularly useful in connection with the closure of railway car door openings so that granular material can be safely carried by such cars.

The present application is a continuation-in-part of my copending applications, Serial No. 465,253, filed October 28, 1954, Serial No. 654,307, filed April 22, 1957, Serial No. 679,842, filed August 23, 1957, and Serial No. 739,080, filed June 2, 1958, all now abandoned.

The usual railway boxcars are provided with a door frame formed of wooden columns or beams, or of members having wooden nailing strips secured thereto. Spaced laterally of the door frame are additional vertical posts or studs which reinforce the side walls of the car. The temporary closure usually comprises a fibrous sheet body which is reinforced with horizontally-extending, flat, flexible metal straps which overlie the frame of the door and which are nailed to the vertical beams of the door frame. Repeated nailing into the door frame weakens the structure, and the door frame or its nailing strip can become splintered or cracked and thereafter is not sufficiently strong to hold the nails.

Additionally, the weight of the cargo tends to bow the flexible fibrous door outwardly, and this, in turn, applies a stress to the door posts, tending to bow or bend them inwardly. The stress applied to the door posts occurs at the outset due to the tensioning of the horizontally-extending straps. Initially, the strap tensioning is accomplished by driving double-headed nails to the straps and into the posts at inclinations so as to draw the straps to a taut condition. Unfortunately, after one strap has been drawn taut, the adjacent strap, as it is being tension nailed, brings about an additional bowing of the posts, and this tends to loosen the adjacent, already secured strap. It is important that the straps be equally tensioned, because if there is one loose strap which fails to support the paper sheet, etc., the sheet can readily crack or tear and result in the loss of valuable cargo.

Another difficulty experienced with door posts in railway cars is that the innermost posts to which the grain door is attached are not directly connected to the inner lining of the car and the post can turn, or partially turn, because of the outward stress exerted by the flexible door body when it bulges outwardly under the weight of grain, etc. The common practice is to place a nailing strip over the inner face of the door, and the nailing strip may itself rock or turn under the outward pull of the bulging grain door body. Further, the door post or nailing strip, by reason of continuous use, often becomes chipped or weakened as pointed out above, and this, along with the rocking of the grain door about the corner of the post or strip (as the door bulges outwardly) tends to draw the fastening means from the post or strip.

I have discovered that the foregoing problem can be effectively solved by providing a metal tie strip or extension between the nailing strip or door post and a laterally spaced stud, while at the same time utilizing the tension of a reinforcing door strap itself to immobilize or reinforce the tie connection.

It is, therefore, a principal object of the invention to provide a temporary closure equipped with reinforcing

2

straps wherein the straps are secured not only into the door posts of a doorway-equipped vehicle, but in which are additionally provided tie strips or extension straps between the door posts and a spaced stud, or the like. Another object is to provide an effective means and method for securing a grain door against the possibility of failure by reason of a weakened door frame and to provide a further safeguard against even concealed weaknesses in the door frame.

Still another object is to provide, in combination with a car structure in which a stud is supported at a spaced distance laterally from a door post and is anchored to the wall of the car, a strap forming an extension of a grain door strap for connecting the stud and door post.

Yet another object is to provide, in combination with a freight vehicle doorway, a temporary closure equipped with flat metal straps having separate extensions at the ends thereof for securement to interior portions of the car spaced laterally of the doorway framing members, the connection of the strap extension to the car wall being into a stud, or the like, with the studs being spaced from their associated doorway framing members a distance sufficient to dispose the extension at substantially a right angle to its associated stud, whereby the nails employed to secure the straps to the studs are stressed primarily in shear.

Other objects and advantages of this invention may be seen as this specification proceeds.

The invention is described in conjunction with illustrative embodiments in the accompanying drawing, in which—

FIGURE 1 is a broken perspective view of a railway car equipped with a door frame and with a door closure therefor having tie straps or extensions embodying my invention;

FIG. 2 is a longitudinal sectional view of the structure shown in FIG. 1;

FIG. 3 is a broken perspective view of the strap structure removed from the door panel;

FIG. 4 is an enlarged fragmentary sectional view of a closure-equipped car, similar to the showing of FIG. 2 but in which a modified form of the invention is employed;

FIG. 5 is a perspective view of a modified form of strap structure embodying the invention; and

FIG. 6 is a fragmentary perspective view of yet another form of strap structure embodying teachings of the invention.

In the illustration given in FIGS. 1, 2 and 3, the numeral 10 designates a panel having the end portions thereof secured to the frame members or door posts 11 of a railway car 12. The panel 10 may be formed of any suitable material for retaining grain or other substances. In the specific illustration given, corrugated board is employed, and there is provided at the bottom of the board a flap 13 adapted to lie against the floor of the car. There may be provided on the sides of the panel side flaps 14 formed by providing scored or weakened vertical lines 15 along each side of the panel 10. A single panel 10 may be employed, or there may be used in combination with panel 10 a series of panels thereabove to form a door closure of any desired height. However, it is believed sufficient for the purpose of the present invention to describe a single panel 10, as set out in FIG. 1.

In the illustration given, particularly in FIG. 2, it is seen that an outer liner sheet 16 is employed in conjunction with the remainder of the corrugated panel 10 to support horizontally-extending, equally vertically spaced-apart, flat metal straps 17. Thus, the straps 17 are positioned interiorly of the composite panel 10, which additionally includes a corrugated core 10a having the flutes thereof extending vertically and which core is lined or

surfaced on the interior side with an inner liner sheet 16a.

In the structure shown in FIGS. 1-3, inclusive, the straps 17 are provided with equally spaced-apart nail openings 18, and the ends of at least some of the straps 17 are connected by means of a rivet 19 to an extension strap segment 20. The extension strap advantageously may be constructed of the same material as the straps 17, which usually are constructed of 18 to 20 gauge black steel having a width of the order of 1-2". The length of the straps 17 is established according to the width of the doorway to be closed by the panel 10, doorways of different widths occurring in different freight cars, and the number of straps 17 employed per panel may also vary, and so also the number of extensions 20.

The extension segment 20 is also provided with equally spaced-apart nail openings 21 so that the same may be secured by nails 22 to the studs or beams 23 with which the railway car 12 is provided. As shown more clearly in FIG. 3, the segment or strap extension 20 may be folded inwardly, so as to lie against the strap 17 (the panel 10 being omitted for the sake of clarity), thus providing no dangerous extension or hazard. If desired, the segment 20 may be secured by gummed paper tape to the panel 10 during transit so as to hold it accurately in alignment with the strap 17. This structure actually reduces the hazard because it stiffens the outer end portions of the strap 17 and the two aligned straps provide a blunt edge which is less dangerous than the narrow edge of the single strap end. When it is desired to extend the straps 17, the segment 20, as shown at the right-hand side of FIG. 3, may be swung outwardly to the position shown. Thus there is provided a safe form of grain door structure which may be shipped with a minimum of hazard and, when desired, the extension 20 may be swung outwardly to engage a side stud 23 so as to be anchored thereto. Even where the door frame, after considerable use and after bearing nail openings, may appear to be sound, it will often be advisable to extend the straps through the use of the segments 20 to provide the additional safeguard as illustrated best in FIG. 1.

In some instances, it may be desirable to swing the extension segments 20 into folded inner position, as illustrated at the left-hand side of FIG. 3 and to nail the strap ends in its relation to the door frame 11. For this purpose, I prefer to have the openings 21 of the segments 20 and the openings 18 of the straps 17 brought into complete alignment so that a nail passing through the strap 17 will also pass through an aligned opening in the segment 20.

With the structure disclosed, it is found that grain can be shipped with greater safety and less splitting and breaking of the grain doors because of the equal tensioning of the straps which is not only accomplished in the installation of the door but which is maintained thereafter during the use of the door under load. As the grain bulges out the panel 10 (see FIG. 2), and as the door flexes inwardly and outwardly under the backing, jerking, humping, bumping, etc., of the freight train, the door posts are held rigidly against bending in any portion thereof without turning under the rocking strains imposed by grain loads so that the straps throughout the operation maintain a uniform support of the door panel 10. Even though the door posts 11 be weakened by previous use, the door posts continue to serve as an effective anchor as the door 10 flexes about it so that the strain is transmitted about the post corner and in a direct line at substantially right angles to the retaining nails 22 in stud 23. Thus, these retaining nails are stressed primarily in shear and are effectively insulated from any stress tending to withdraw them from the stud.

As pointed out previously, the panel may be equipped with the side flaps 14 so as to expose the interiorly positioned straps 17 for nailing as by nails 24. The flaps 14 thereafter can be secured by nails 25 which also extend into the framing posts 11. Alternatively, the side flaps 75

14 may be omitted and the panel 10 equipped with nail position indicia.

While I have shown the invention in one embodiment in which the extensions 20 are pivotally mounted upon the straps 17 by the rivets 19, it will be understood that other means may be employed advantageously in some instances. For example, a staple 26 (see FIG. 5) may be passed through pairs of openings 18 in the strap 17 and corresponding openings 21 in the extension 20, and the legs of the staple 26 clinched against the extension 20 to provide a secure union. Alternatively, the legs of the staple 26 can be forced into the frame members 11, thereby eliminating the need for clinching. If desired, the staple segments may be taped with the extension 20 to the panel 10 for convenience in shipment to the site of installation.

In another modification of the invention (see FIG. 6), I again provide a tie strap 20 which is equipped with spaced nail openings 21. Intermediate the nail openings 21, the strap 20 has flat fastening segments 27 struck therefrom and extending inwardly. The segments 27 may be equipped with pointed ends 28 which facilitate the insertion of the segments 27 into the nail openings 18 of the main strap 17. The fastening segment-equipped strap 20 of FIG. 6 is secured to the end portion of a strap 17 in a position overlying the framing post 11 so that the post 11 may provide a support surface for the convenient clinching of the segments 27 against the straps 17.

30 The extension strap 20 enables the door structure to be erected by a single operator, since, when the extension strap is secured to the end portion of a door strap 17, the operator simply handles the outer end of the extension strap in securing it to the stud 23 in the same way he has handled the original door strap in securing it to the vertical beam 11. Also, the strap 17 equipped with a strap extension 20 provides a structure in which the strap elements have substantially no play between them and form a rigid reinforced area over the door frame 11.

As has been noted, the character of the freight vehicle in which the inventive closures are installed, varies somewhat. In FIG. 4, there is seen a fragment of a grain-carrying freight car in which the stud 23 is masked by inner side wall boards 29. Again, as in FIG. 2, the panel generally designated 10 is seen bowed outwardly in the doorway opening in the condition it would be when a granular load (not shown) is bearing against it. The outer sheathing of the car is designated 31.

As before, the panel 10 includes liners 16 and 16a on opposite sides of a corrugated core 10a and with flat metal straps 17 provided interiorly of the composite panel 10. Strap extensions 20 are provided which are nailed as at 22 by the usual double-headed nails to the studs 23. The end of extension 20 adjacent the panel 10 is secured thereto, and also to the post 11, by means of the nail 24. As pointed out previously, the nail 24 and the nail 22 may be advantageously inclined relative to the doorway, as this is seen in dotted line and designated by the numerals 24a and 22a, respectively.

60 In the illustration given in FIG. 4, the extreme end portion of the panel 10 may be secured to the inner liner 29 by means of a nail 32 in conjunction with a side batten 33, in accordance with conventional procedure.

70 In all of the embodiments of the invention, an extremely useful operation is achieved in that the strap extension remains immobile irrespective of the buffeting of the door panel 10. It will be appreciated that a granular load surges to and fro considerably during transit and where the panel securement is merely to the framing posts, there is a tendency to place the securing nails in tension so as to literally rip them out of the posts. The strap extensions, being of a length corresponding to the spacing of the studs, or greater, afford an extremely satis-

factory anchor for the door panel in a position where the buffeting of the panel is of no consequence. In the inventive form seen in FIGS. 1-4, the extension straps 20 are conveniently pivoted into positions overlying the studs or inner wall, as the case may be, and quickly secured with a minimum of time. Even though the securing nail for an extension strap be driven in at an angle, it is still stressed primarily in shear because of the essential right angle relationship of the extension strap to the stud; alternatively, the parallel relationship of the extension strap and the inner wall 29.

While, in the foregoing specification, I have set forth specific structures in considerable detail for the purpose of illustrating embodiments of the invention, it will be understood that such details of structure may be varied widely by those skilled in the art without departing from the spirit of the invention.

I claim:

1. In combination with a car having vertical door posts and vertical studs spaced therefrom, a flexible door panel adapted to extend between said posts in overlapping relation therewith, vertically spaced, flexible, flat straps in said panel to support the same and having end portions overlapping said door posts, said strap ends being equipped with separate extension tie portions, said extension tie portions overlapping said studs, means connecting said extension tie portions and said strap end portions, and nails securing each strap to said posts and other nails anchoring said extension tie portions to said studs laterally of said posts, whereby said tie portions connect said studs to said posts, each of said studs being spaced from its associated door post a distance sufficient to dispose said tie portion at substantially right angles to said stud so as to stress said other nails principally in shear.

2. The structure of claim 1 in which said connecting means comprises a rivet.

3. The structure of claim 1 in which said connecting means comprises a staple.

4. The structure of claim 1 in which said connecting means comprises a nail which additionally secures said strap end portions to said posts.

5. The structure of claim 1 in which said extension tie portions are equipped with flat segments struck from an end thereof, said flat segments providing said connecting means.

6. In combination with a grain-carrying freight car having a door opening defined by vertically-extending framing posts, said car being equipped with vertically-extending studs spaced horizontally of said posts, a temporary closure extending across said door opening and overlapping said posts, said closure comprising a flexible paperboard panel disposed generally in a vertical plane and interiorly equipped with a plurality of horizontally-extending, equally vertically spaced-apart flat metal straps adjacent the outer panel side, said straps being equipped at the ends thereof, with a plurality of horizontally-spaced nail holes, pointed securing means extending through said nail holes into said posts for securing said panel to said posts, a flat metal strap extension member at each end of one of said straps, each of said members being equipped with a plurality of horizontally-spaced nail holes and disposed in aligned, overlapping relation with said one strap, securing means extending through aligned nail openings in each overlapped member and strap to tie the two together, and pointed securing means extending through

the nail openings of said members securing the same to said studs, whereby each post and its adjacent stud co-operate in supporting said straps against horizontal movement under stress of grain carried by said car and the pointed securing means extending through the nail openings of said members securing the same to said studs are stressed primarily in shear.

7. The structure of claim 6 in which the pointed securing means extending through said nail holes into said posts for securing the panel straps to said posts also extend through aligned nail openings in each overlapped member and strap to tie the two together.

8. The structure of claim 6 in which the said securing means comprises a rivet.

9. In combination with a freight vehicle having a sidewall, a doorway in said sidewall defined by spaced-apart vertical framing posts, said wall being equipped with vertically-extending studs spaced from said posts, a flexible paperboard closure extending across said doorway in overlapping relation with said posts, said closure comprising liner sheets and spaced-apart flat metal straps positioned between said liner sheets, each of said straps, at least at the end portions thereof, being equipped with a plurality of horizontally-spaced nail openings, nails extending through said strap end portions securing the closure to said posts, a plurality of said straps being equipped with separate strap extensions pivotally connected to said end portions and movable from a position substantially overlapping said closure to a position overlapping an adjacent stud, said strap extensions being equipped with spaced-apart nail openings, and nails extending through said strap extension nail openings into said adjacent studs.

10. In combination with a freight vehicle having a sidewall, a doorway in said sidewall defined by spaced-apart vertical framing posts, said wall being equipped with vertically-extending studs spaced from said posts, a flexible paperboard closure extending across said doorway in overlapping relation with said posts, said closure comprising liner sheets facing the car interior and spaced-apart flat metal straps positioned between said liner sheets, each of said straps, at least at the end portions thereof, being equipped with a plurality of horizontally-spaced nail openings, nails extending through said strap end portions securing the closure to said posts, a plurality of said straps being equipped with separate strap extensions pivotally connected to said end portions and movable from a position substantially overlapping said closure to a position overlapping an adjacent stud, said strap extensions being equipped with spaced-apart nail openings, said extension and strap nail openings being aligned, a rivet extending through aligned nail openings providing said pivotal movement, and nails extending through said strap extension nail openings into said adjacent studs, said strap nails and said extension nails being spaced apart sufficiently to dispose each extension strap at substantially a right angle to its associated stud whereby said extension nails are stressed primarily in shear.
